(57) **CLAIM**

The ornamental design for a tubular storage bag, as shown and described.

DESCRIPTION

FIG. 1 is a perspective view of my new tubular storage bag design in a closed state;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a cross-sectional view taken along line 8-8 of FIG. 1; and,

FIG. 9 is a further perspective view showing my new tubular storage bag design in an open state, with an exemplary object positioned therewithin.

The broken lines showing the exemplary object depict environmental subject matter and form no part of the claimed design. All other broken lines depict portions of the tubular storage bag that form no part of the claimed design.
